METHOD OF MAKING MILKER PAILS

Fernand J. J. J. Henrard, Remicourt, Belgium,
assignor to Babson Bros. Co., a corporation of
Illinois

Continuation of application Serial No. 648,112,
February 16, 1946. This application December
11, 1948, Serial No. 64,754

8 Claims. (Cl. 29—148.2)

1

This invention relates to a method of making milker pails, and more particularly milker pails of the suspended type.

This application is a continuation of my application Serial No. 648,112, filed February 16, 1946, now abandoned.

Suspended milkers, as of the type shown in McCornack Patent 1,859,213, make use of a pail of substantial diameter with a lid opening of less than half such diameter, and with a height of the same order. For example, a commercial suspended milker now being sold on the market uses a pail with a diameter of about 15½ inches, a maximum height of about 7½ inches, and an opening in the top portion with a diameter in the neighborhood of 7 inches. In usage this opening is closed by a lid sealed vacuum tight to the pail, the lid having connector nipples for the milker inflations and also carrying the pulsator and its connections. The general construction and operation of a milker of this type is well known and will not be described further.

All milkers of the suspended type heretofore made have involved the use of a seam of the overlapping type between upper and lower sections of the milker pail. That is, the milker pail normally comprises an upper part made in one draw or series of draws, at least in one forming operation; and a lower part separately drawn or formed. Heretofore the parts have been so arranged that adjacent edges overlapped and the resultant seam was then spot welded or otherwise fastened. A small collar or annulus was then usually welded on around the neck portion or opening to provide a horizontal upper surface adapted to receive the lid. The seams thus formed were undesirable, not so much in that they spoiled the appearance of the milker pail, although this was to some extent the case, but primarily because they provided a lodging place for bacteria which could not readily be washed out in the usual washing and sterilizing operation of the milking equipment. Any such pocket or focal point of bacteria, of course, tends to contaminate new milk at each milking with undesirable results in the way of a higher bacterial count, reducing its value at the milk station, etc.

All conventional methods of making a butt welded construction have heretofore failed with a pail of this type, in view of the relatively small opening in the upper part of the pail, which prevented any support or registry of the pail parts interiorly by previous conventional methods.

I have devised a new supporting apparatus for and method of welding milker pail parts to-

2

gether which overcomes these previous difficulties and objections, and which makes what is for all practical purposes a "seamless" pail, a pail made in accordance with my inventions having completely smooth inner and outer walls which not only have the desirable appearance of "seamless" construction, but which also completely avoid any chance of unwashable pockets on the inner surface of the seam.

10 Other features and advantages of my inventions will be apparent from the following specification, and the drawings, in which:

Figure 1 is a top view, partly broken away, of the two main pail parts with supporting apparatus therein for use during welding; Figure 2 is a transverse sectional view along the line 2—2 of Figure 1; Figure 3 is a partial enlarged elevational view of the pressure applying portion of the supporting apparatus, along the line 3—3 of Figure 1; Figure 4 is a plan view of apparatus used in rolling the welded seam, with a pail shown in place therein; Figure 5 is a side elevational view of the apparatus shown in Figure 4; Figure 6 is a transverse sectional view of the supporting apparatus used interiorly of the pail during welding, along the line 6—6 of Figure 1; and Figure 7 is a cross sectional view similar to Figure 6 but of supporting apparatus used during rolling of the seam.

15 The essential features of my invention are rolling of the welded seam from the outside with substantial pressure to eliminate non-uniformities, supporting the seam interiorly during such rolling, and supporting the adjacent edges of the upper and lower pail parts interiorly during welding. While these inventions may be employed for use in various types of apparatus, so that it will be understood that variations and changes are contemplated so long as they come 20 within the scope of the appended claims, I am describing only a single preferred method of and apparatus for achieving the desired pail construction.

25 In the particular embodiment of my invention illustrated herewith, a milker pail 10 is shown as having main upper and lower parts 10a and 10b. The specific curvatures and relations of these parts may, of course, be varied to secure any finished pail desired; and the upper part would have a rim or annulus welded to the neck portion 10a around the opening 11 together with a handle, and the lower part may have a supporting ring welded or otherwise fastened to the bottom thereof, as desired, to complete the 30 finished pail, none of these parts being shown 35

since they have no connection with the present invention, except that the seam between the neck portion 18a' and the annulus or ring part fastened thereto may be accomplished in a manner similar to that which will be described for the main seam between the two parts 10a and 10b of the milker pail.

Within the milker pail is supporting apparatus comprising as its principal parts the two sector members 12 and 13. These two parts are separately but pivotally connected together at one end, as by use of a pin 14 in cooperating grooves or recesses in the adjacent ends of the sector parts; and are adapted to be separated or moved apart by actuating means at their other ends. This actuating means comprises a wedge-like member 15 adapted to cooperate with angularly disposed edges on the cooperating ends of the sector members 12 and 13, as may be best seen in Figure 3. A bridging member 16 is adapted to span the opening between the sector members beneath the wedge member 15; and a stud 17 provides threaded means for pulling the wedge down (as the stud is rotated by a wrench) to force these ends of the sector members apart. The sector members are so formed that the outer or arcuate surfaces thereof have curvatures conforming, in expanded position, to the interior curvature of the pail adjacent the seam, the wedging member 15 being provided with a curved edge engaging the pail wall and completing support for the inner surface of the wall completely around the pail body adjacent the seam.

As may be best seen in Figure 6, at least the outer surface of the sector members is composed of copper, this being shown in Figure 6 as an additional piece 12a on a steel body portion 12b of the sector member 12, although it will be understood that other materials may be used. This outer surface of the sector member is provided with a central depression or groove identified as 12a' in Figure 6. This groove is designed to register with the junction of the edges of the upper and lower parts of the pail body during welding of the seam, as may be best seen in Figure 2. Engagement of the supporting member with the inner walls above and below this junction line ensures perfect registry and maintenance of position during welding; while the groove permits heat to be developed locally at the joint and any small local expansions to take place. Maintenance of the inner supporting apparatus at the proper height above the bottom of the pail is ensured by the provision of spacer means on each member, as for example the legs 18a-c on the sector member 12 and the corresponding legs 19a-c on the sector member 13.

After the seam has been welded it comprises a portion which is generally somewhat thicker than the adjacent portions of the wall on each side, and which has local irregularities in the way of bumps and depressions. I have found that if the joint is supported interiorly of the pail and rolled under substantial pressure applied exteriorly, the metal at the welded seam can be worked so as to eliminate these irregularities and result in a wall thickness and smoothness at the seam corresponding to that of the material on each side, so that when the seam is buffed the pail is apparently of one-piece construction with no seam whatsoever. This is particularly true where the stainless steel forming the preferred pail walls is butt welded by the atomic hydrogen method, without the

use of any additional filler material, so that all material at the joint is stainless steel.

One method of readily rolling the joint while applying the very substantial pressures necessary is shown in Figures 4 and 5. The rolling apparatus there disclosed comprises a base 20 on which is rotatably mounted a supporting table 21 adapted to receive the pail 10. Symmetrically spaced about the table 21 are mounting brackets 22, 23 and 24 supporting rollers 25, 26 and 27, the spacing of the parts being such that when the milker pail is on the supporting table the middle of the outer surface of each of the rollers bear against the welded seam, as may be best seen in Figure 5. Each roll preferably is of hardened steel and formed with a very slight divergence from its center line, as for example by having its surface taper back from its center line to each side at about 1° divergence inward from a line through the outer surface parallel to the axis of the roller.

In order to apply the necessary pressure and effect the rolling working of the welded seam rapidly, one roll, as the roll 26, is slidably mounted in its mounting bracket, and adapted to be forced inwardly toward the pail by operation of some threaded means, as the stud 28 threaded into a fixed part of the bracket 23 and bearing against a slidably roll-carrying block 29. One of the rolls is preferably power rotated, this being shown as the roll 27 operated through suitable reduction gearing comprising the gear 30 and pinion 31 by the motor 32.

During this rolling operation the welded seam is supported interiorly by a supporting arrangement which is analogous to that shown and described in more detail heretofore, except that the cross section of the outer surface of the sector members is somewhat different, as may be seen in Figure 7. Here the sector member 42 (corresponding, for example, to the sector member 12 in general construction) comprises a solid steel body portion having at least the outer surface thereof hardened. Even more important, the outer surface has a straight central portion 42a and slightly inwardly diverging side portions 42b and 42c. The central portion may, for example, have a width of about $\frac{1}{2}$ inch; and the side portions may each well be in the neighborhood of $\frac{3}{4}$ inch long (speaking of the cross section) and preferably diverge at a very small angle, as 1°. This shape of the inner supporting means, in conjunction with the shape of the rolls, provides a working effect immediately at the seam which is substantially unimpeded by engagement with portions of the pail wall more than a small fraction of an inch on each side of the seam.

Assuming that the upper and lower pail sections have been properly formed, as by drawing, from stainless steel, the supporting apparatus of the type shown in Figures 1-6 would be placed in the lower portion and the upper portion then placed thereover, with the wedging portion 15 lying immediately beneath the opening 11 in the upper part of the pail. A socket wrench or the like would then be used to rotate the stud 17 and wedge apart the sector members to provide a firm grip or support entirely around the inner walls adjacent the seam line, the situation being then as shown in Figure 2. The adjacent edges of the stainless steel parts would then be butt welded, preferably by the atomic hydrogen procedure, and then the stud 17 would be ro-

tated back until it was threaded out of the bridge member 16, whereupon the wedge portion 15 would be lifted up out of the opening. One sector member and then the other would then be brought up out through the opening 11, this being a very easy and simple procedure once the sector members are separated. The bridge member 16 would then be picked up out of the pail and, if it is a loose piece, the pin 14, although this pin may well be spot welded or otherwise fastened to one of the sector members. Sector members having a cross section of the type shown in Figure 7 would then be inserted through the opening and maneuvered into a position corresponding to that of the sector members used to support the pail walls during welding, whereupon a wedge piece, bridge and stud would be inserted, threaded together, and the stud drawn up with a wrench to force these latter supporting members into tight engagement with the inner wall at the seam, entirely therearound. The pail with this latter supporting means would then be placed on the rolling apparatus, as shown in Figures 4 and 5, and a wrench or other means used to draw up the roll 26 into tighter and tighter engagement with the outer wall of the seam as the motor 32 drove roll 27 to rotate the milker. Because of the symmetry of the roll arrangement, drawing up on the one roll is sufficient to result in a uniform rolling pressure of all three rolls of any amount desired, preferably of at least several hundred pounds. I find it desirable to use relatively high rolling pressure and only to rotate the pail two or three times under high pressure, as continuous rolling and rerolling of the seam at lower pressures sometimes causes a hardening which renders it impossible to make the seam thickness uniform with that of the walls on either side. After the rolling has been properly completed the stud 28 would be backed off, the stud 41 loosened and the supporting parts removed from the pail as described before. The neck flange (not shown) would then be welded in place and this seam also rolled, either with an internal support analogous to that just described or by use of cooperating inner and outer rolls, since the full opening area is available. The main or central seam presents the greatest problem because the diameter of the milker is normally, at this point, two to three times the diameter of the opening 11, so that any conventional apparatus or method for working or rolling a plate or seam is not usable.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A method of making stainless steel milker pails of the suspended type, comprising drawing sheet metal to form the lower part of the pail with an imperforate bottom and generally cylindrical relatively short upstanding walls, drawing sheet metal to form the upper part of the pail with a top and generally cylindrical relatively short depending walls, providing an opening in said top of a diameter not exceeding half that of the pail, abutting the edges of the walls of the two parts, engaging a first collapsible supporting member having an engaging surface of good heat conductivity with the inner surface of the pail

walls in an area lying above and below the abutment line throughout substantially its entire peripheral length to ensure perfect registry and maintenance of position during welding, butt-welding the parts together at the abutting edges, engaging a second collapsible supporting member having a hard engaging surface with the inner portion of the welded seam throughout substantially its entire peripheral length and rolling the welded seam with high rolling pressure and a low number of rerolling traverses to avoid substantial hardening and to thereby make the seam thickness substantially uniform with that of the walls on either side.

15 2. A method of making stainless steel milker pails of the suspended type, comprising drawing sheet metal to form the lower part of the pail with an imperforate bottom and generally cylindrical relatively short upstanding walls, drawing sheet metal to form the upper part of the pail with a top and generally cylindrical relatively short depending walls, providing an opening in said top of a diameter not exceeding half that of the pail and substantially entirely to one side 20 of the center thereof, abutting the edges of the walls of the two parts, engaging a first collapsible supporting member having an engaging surface of good heat conductivity with the inner surface of the pail walls in an area lying above and below the abutment line throughout substantially its entire peripheral length to ensure perfect registry and maintenance of position during welding, said supporting member having an annular groove therearound in registry with said abutment line, butt-welding the parts together at the abutting edges, engaging a second collapsible supporting member having a hard engaging surface with the inner portion of the welded seam throughout substantially its entire peripheral length and rolling the welded seam with high rolling pressure and a low number of rerolling traverses to avoid substantial hardening and to thereby make the seam thickness substantially uniform with that of the walls on either side.

30 3. A method of making stainless steel milker pails of the suspended type, comprising drawing sheet metal to form the lower part of the pail with an imperforate bottom and generally cylindrical relatively short upstanding walls, drawing sheet metal to form the upper part of the pail with a top and generally cylindrical relatively short depending walls, providing an opening in said top of a diameter not exceeding half that of the pail, abutting the edges of the walls of the two parts, engaging a first collapsible supporting member having an engaging surface of good heat conductivity with the inner surface of the pail walls in an area lying above and below the abutment line throughout substantially its entire peripheral length to ensure perfect registry and maintenance of position during welding, butt-welding the parts together at the abutting edges, engaging a second collapsible supporting member having a hard steel engaging surface with the inner portion of the welded seam throughout substantially its entire peripheral length and rolling the welded seam with high rolling pressure applied at three spaced points and a low number 40 of rerolling traverses to avoid substantial hardening and to thereby make the seam thickness substantially uniform with that of the walls on either side.

45 4. A method of making stainless steel milker pails of the suspended type, comprising drawing sheet metal to form the lower part of the pail with an imperforate bottom and generally cylindrical relatively short upstanding walls, drawing sheet metal to form the upper part of the pail with a top and generally cylindrical relatively short depending walls, providing an opening in said top of a diameter not exceeding half that of the pail, abutting the edges of the walls of the two parts, engaging a first collapsible supporting member having an engaging surface of good heat conductivity with the inner surface of the pail walls in an area lying above and below the abutment line throughout substantially its entire peripheral length to ensure perfect registry and maintenance of position during welding, butt-welding the parts together at the abutting edges, engaging a second collapsible supporting member having a hard steel engaging surface with the inner portion of the welded seam throughout substantially its entire peripheral length and rolling the welded seam with high rolling pressure applied at three spaced points and a low number 50 of rerolling traverses to avoid substantial hardening and to thereby make the seam thickness substantially uniform with that of the walls on either side.

55 5. A method of making stainless steel milker pails of the suspended type, comprising drawing sheet metal to form the lower part of the pail with an imperforate bottom and generally cylindrical relatively short upstanding walls, drawing sheet metal to form the upper part of the pail with a top and generally cylindrical relatively short depending walls, providing an opening in said top of a diameter not exceeding half that of the pail, abutting the edges of the walls of the two parts, engaging a first collapsible supporting member having an engaging surface of good heat conductivity with the inner surface of the pail walls in an area lying above and below the abutment line throughout substantially its entire peripheral length to ensure perfect registry and maintenance of position during welding, butt-welding the parts together at the abutting edges, engaging a second collapsible supporting member having a hard steel engaging surface with the inner portion of the welded seam throughout substantially its entire peripheral length and rolling the welded seam with high rolling pressure applied at three spaced points and a low number 60 of rerolling traverses to avoid substantial hardening and to thereby make the seam thickness substantially uniform with that of the walls on either side.

65 6. A method of making stainless steel milker pails of the suspended type, comprising drawing sheet metal to form the lower part of the pail with an imperforate bottom and generally cylindrical relatively short upstanding walls, drawing sheet metal to form the upper part of the pail with a top and generally cylindrical relatively short depending walls, providing an opening in said top of a diameter not exceeding half that of the pail, abutting the edges of the walls of the two parts, engaging a first collapsible supporting member having an engaging surface of good heat conductivity with the inner surface of the pail walls in an area lying above and below the abutment line throughout substantially its entire peripheral length to ensure perfect registry and maintenance of position during welding, butt-welding the parts together at the abutting edges, engaging a second collapsible supporting member having a hard steel engaging surface with the inner portion of the welded seam throughout substantially its entire peripheral length and rolling the welded seam with high rolling pressure applied at three spaced points and a low number 70 of rerolling traverses to avoid substantial hardening and to thereby make the seam thickness substantially uniform with that of the walls on either side.

4. A method of making stainless steel milker
75 pails of the suspended type, comprising drawing

sheet metal to form the lower part of the pail with an imperforate bottom and generally cylindrical relatively short upstanding walls, drawing sheet metal to form the upper part of the pail with a top and generally cylindrical relatively short depending walls, providing an opening in said top of a diameter not exceeding half that of the pail and substantially entirely to one side of the center thereof, abutting the edges of the walls of the two parts, engaging a first collapsible supporting member having an engaging surface of good heat conductivity with the inner surface of the pail walls in an area lying above and below the abutment line throughout substantially its entire peripheral length to ensure perfect registry and maintenance of position during welding, said supporting member having an annular groove therearound in registry with said abutment line, butt-welding the parts together at the abutting edges, engaging a second collapsible supporting member having a hard steel engaging surface with the inner portion of the welded seam throughout substantially its entire peripheral length and rolling the welded seam with high rolling pressure applied at three spaced points and a low number of rerolling traverses to avoid substantial hardening and to thereby make the seam thickness substantially uniform with that of the walls on either side.

5. A method of making stainless steel milker pails of the suspended type, comprising drawing stainless steel sheet metal to form the lower part of the pail with an imperforate bottom and generally cylindrical relatively short upstanding walls, drawing stainless steel sheet metal to form the upper part of the pail with a top and generally cylindrical relatively short depending walls, providing an opening in said top of a diameter not exceeding half that of the pail and substantially entirely to one side of the center thereof, abutting the edges of the walls of the two parts, engaging a first collapsible supporting member having an engaging surface of good heat conductivity with the inner surface of the pail walls in an area lying above and below the abutment line throughout substantially its entire peripheral length to ensure perfect registry and maintenance of position during welding, said supporting member having an annular groove therearound in registry with said abutment line, butt-welding the parts together at the abutting edges by atomic hydrogen welding, engaging a second collapsible supporting member having a hard steel engaging surface with the inner portion of the welded seam throughout substantially its entire peripheral length and rolling the welded seam with high rolling pressure applied at three spaced points and a low number of rerolling traverses to avoid substantial hardening and to thereby make the seam thickness substantially uniform with that of the walls on either side.

6. A method of making milker pails of the suspended type, comprising drawing hard sheet metal to form the lower part of the pail with an imperforate bottom and generally cylindrical relatively short upstanding walls, drawing hard sheet metal to form the upper part of the pail with a top and generally cylindrical relatively short depending walls, providing an opening in said top of a diameter not exceeding half that of the pail, abutting the edges of the walls of the two parts, holding the pail parts with their edges

in registering engagement with a first supporting means adapted to provide the support necessary during welding, butt-welding the parts together at the abutting edges, engaging a second

5 supporting member, this member being collapsible and having a hard engaging surface, with the inner portion of the welded seam throughout substantially its entire peripheral length and rolling the welded seam with high rolling pressure and a low number of rerolling traverses to avoid substantial hardening and to thereby make the seam thickness substantially uniform with that of the walls on either side.

7. A method of the character claimed in claim 15 6 wherein the collapsible supporting member has a hard steel engaging surface and the rolling is effected by pressure applied at three spaced points on the outside of the seam.

8. A method of making milker pails of the suspended type, comprising drawing hard sheet metal to form the lower part of the pail with an imperforate bottom and generally cylindrical relatively short upstanding walls, drawing hard sheet metal to form the upper part of the pail

20 with a top and generally cylindrical relatively short depending walls, providing an offset opening in said top, abutting the edges of the walls of the two parts, holding the pail parts with their edges in registering engagement with a first

25 supporting means adapted to provide the support necessary during welding, butt-welding the parts together at the abutting edges, engaging a second supporting member, this member being collapsible and having a hard engaging surface,

30 35 with the inner portion of the welded seam throughout substantially its entire peripheral length and rolling the welded seam with high rolling pressure and a low number of rerolling traverses to avoid substantial hardening and to

40 thereby make the seam thickness substantially uniform with that of the walls on either side.
